(57) **CLAIM**

The ornamental design for a faucet spout, as shown and described.

DESCRIPTION

FIG. 1 is a perspective view of a faucet spout showing my new design;

FIG. 2 is another perspective view of the faucet spout;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an environmental view showing the faucet spout mounted on a sink deck; and,

FIG. 10 is another environmental view showing the faucet spout being pulled out of the sink deck a distance in use.

The broken line showing of a portion of the spout in FIG. 8 and environment in FIGS. 9 and 10 is included for the purpose of illustrating and forms no part of the claimed design.
